UNITED STATES PATENT OFFICE

2,489,464

CHALK CONTAINER

Joseph W. Roland, Aberdeen, Md.

Application November 22, 1946, Serial No. 711,520

1 Claim. (Cl. 273—20)

1

My invention relates to equipment for pool rooms and more particularly to containers for chalk adapted to be used for chalking cue tips.

The object of my invention is to provide a container adapted to receive and hold a piece of pool chalk and provided with a plurality of holes to permit a pool cue to be inserted into the container and to be chalked and to eliminate such difficulties encountered heretofore as breakage of the pool chalk, staining the clothing with chalk, accumulation of chalk dust on the pool table and the like.

Another object of my invention is to provide a chalk container making possible a better and more complete chalking of the cue stick tip for a longer period of time and to save chalk, by varying the position of the chalk in the container when holes are worn in the chalk so that a fresh surface or surfaces for chalking is presented as needed and substantially the entire chalk is eventually used up.

Other objects of my invention may appear in the following specification describing my invention with reference to the accompanying drawing illustrating a preferred embodiment of my invention.

It is, however, to be understood that my invention is not to be limited and restricted to the exact construction and combination of parts described in the specification and shown in the drawing, but that such changes and modifications can be made, which fall within the scope of the claim appended hereto.

In the drawing:

Figure 1 is an elevational side view of the pool chalk container according to my invention.

Figure 2 is a sectional view taken on line 2—2 in Figure 1.

Figure 3 is a sectional view taken on line 3—3 in Figure 1.

Figure 4 is a perspective view of a chalk container, and

Figure 5 is an elevational side view of a modified form of the chalk container according to my invention.

Referring now in detail to the drawing, the chalk container forming the subject matter of my invention has a substantially cylindrical body 10. The interior of the body 10 is hollow and has a square cross section as shown at 11, so that it is adapted to receive a piece of billiard or pool chalk of the usual shape and size. A plurality of pairs of holes 12 are provided in the circumferential wall of the body 10 and are arranged so that the vertical longitudinal center plane of each pair of

2

holes 12 extends parallel to a vertical diametrical center plane of the cylindrical body and that the axes of each pair of holes 12 is laterally offset relative to the corresponding vertical center plane of the body 10.

The holes 12 of each pair are arranged furthermore, so that the same are laterally and vertically offset relative to each other distances approximately equal to the diameter of each hole. This 10 staggered arrangement of the holes permits substantially the entire chalk to be used up because a 90° displacement of the chalk presents a fresh surface to each hole 12.

The lower end of the cylindrical body 10 is 15 closed by a bottom 13 having a centrally located hole 14 therein of a somewhat greater diameter than the diameters of the holes 12 in the circumferential wall of the body 10.

The upper portion of the cylindrical body 10 20 is provided with an outside thread 15 and a screw cap 16 is adapted to engage this thread and to close the open top end of the body 10.

On the inside of the top of the screw cap 16 an 25 annular boss 17 is formed integrally with said cap and is arranged coaxially therewith. It extends downwardly therefrom into the cylindrical body 10 and is adapted to engage a piece of pool chalk 18 placed into the hollow in said body.

A suspension ring 19 has a downwardly extending 30 stem 20 projecting through a centrally located hole 21 in the screw cap 16. A swivel disk 22 is fastened to the lower end of the stem 20 and is located inside the annular boss 17 on the screw cap 16.

In Figure 5 a modified form of the pool chalk 35 container according to my invention is illustrated. The construction of this modified container is practically identical with the construction described above, but the body 23 of the modified container is substantially globular. The body 23 has a hollow 24 therein of a square cross section adapted to receive a piece of pool chalk.

On the upper part of the body 23 a short outwardly threaded neck 25 is provided and a screw cap 40 45 26 is adapted to engage this neck and close the open upper end of the body. An annular boss 27 extends downwardly from the inside of the top of the screw cap 26, with which it is integrally and coaxially formed. The inner end of said boss is adapted to engage a piece of pool chalk placed in the body 23.

A plurality of holes 28 are provided in the body 23 so that a billiard cue can be inserted therethrough for the purpose of chalking the tip of said cue (not shown).

A suspension ring 29 is attached to the screw cap 26 in the manner described above for the suspension ring 19.

The above description shows clearly how a piece of pool chalk can be secured in a container and how a billiard cue tip can be chalked by inserting the cue in any one of the holes in the body of the container without soiling the hands or clothing with the chalk.

Having described my invention I claim as new 10 and desire to secure by Letters Patent:

A container for pool chalk including a body formed with a central cavity adapted to receive a piece of pool chalk therein, said body being formed with a circumferential series of substantially laterally-directed holes permitting access to said chalk, adjacent holes being laterally and vertically offset relative to each other, said holes being disposed in pairs with the holes of each

pair having parallel axes, said axes of each pair being parallel to and on opposite sides of a vertical diametrical center plane of said cavity, and

5 said axes of each pair of holes lying parallel to and on opposite sides of a horizontal diametrical center plane of said cavity.

JOSEPH W. ROLAND.
